UNITED STATES PATENT OFFICE

141,151

DESIGN FOR A DISPLAY TABLE

Harry H. Schwartz, West Los Angeles, Calif., assignor to Ed C. Bretter, Sidney Deutch, and Harry H. Schwartz, copartners doing business as California Fabric Company, Los Angeles, Calif.

Application January 9, 1945, Serial No. 117,363

Term of patent 14 years

(Cl. D80—9)

To all whom it may concern:

Be it known that I, Harry H. Schwartz, a citizen of the United States, residing at West Los Angeles, in the county of Los Angeles and State of California, have invented a new, original, and ornamental Design for a Display Table, of which the following is a specification, reference being had to the accompanying drawing forming a part thereof.

I claim:

The ornamental design for a display table, as shown.

HARRY H. SCHWARTZ.
